UNITED STATES PATENT OFFICE.

JOSEPH McLEAN, OF SOUTH MANCHESTER, CONNECTICUT.

FURNACE.

Application filed October 29, 1924. Serial No. 746,613.

My invention relates more especially to that class of heaters of the smaller type that are employed for heating residences, more especially with the use of steam or water, and an object of my invention, among others, is the provision of a heater having novel means for raising the temperature of the water employed in the heater whereby the efficiency of the heater is increased.

One form of heater embodying my invention and in the construction and use of which the objects herein set out, as well as others, may be attained, is illustrated in the accompanying drawings, in which—

Figure 1 is a view in front elevation of that portion of a furnace or heater in proximity to and including the usual feed opening for the supply of fuel to the furnace.

Figure 2 is a top view of the same with parts broken away to show construction.

Figure 3 is a view in section through the furnace door on a plane denoted by the dotted line 3—3 of Figure 2.

Figure 4 is a detail view, scale enlarged, showing the construction of the hinges for said door to provide for the flow of water to the heating compartments within the door and in section on a plane denoted by the dotted line 4—4 of Figure 2.

In the accompanying drawings the numeral 5 indicates that portion of the jacket of a furnace or heater containing the opening for the supply of fuel to the heater, such opening 6 being formed within a door frame 7 secured to the jacket. A door 8 is provided for the opening 6, this door being mounted to swing upon hinge supports including ears 9 preferably integral with the frame 7, this hinge support being especially constructed for the flow of water and in a manner to be hereinafter described. The frame is also provided with a projection 10 the outer edge of which constitutes a seat for the door.

A reservoir 11 comprises a projection extending inwardly from the inner face of the door 8 and to a considerable distance within the furnace, in the structure herein shown such projection extending substantially one-half way across the firepot. This projection has double walls at its top, bottom, sides and back, between which walls a water compartment 12 is formed. This projection is in the form of a hood and, therefore, chamber 13 exists in the central portion of the compartment and a draught tube

14 extends through said chamber opening at the face of the door and at the back of the projection 11 for the supply of oxygen within the firepot, which passage may be controlled by a damper 15, of any usual form and construction.

Hinge ears 16 are formed integral with the door 8 at the back edge thereof, these ears being hollow to provide chambers 17 communicating with the compartments 12. Circulating pipes 18—19 are connected with the chambers 17, each of said pipes extending to any suitable container for water to be heated, as the dome of the furnace, to which furnace the door 8 is attached, or to a tank or other receptacle, the pipes 18—19 being so connected as to provide for a circulation of water from and to said tank or dome and through the chambers 17 and the compartment 12. In the structure herein shown nipples 20 are secured to the hinge ears 16 and project through the hinge ears 9, said nipples including a stuffing box 21 provided with the usual packing and a gland 22 for packing the joint, in a manner that will be readily understood.

The projection 11 is curved as at 23 on one side to permit the door 8 to be opened without obstruction by said projection. This construction provides a heating compartment located directly over the fire within the firepot, and extending into said firepot to a distance to enable extremely beneficial results to be obtained in the heating of water within the compartment 12, and at the same time this heating element does not obstruct the operations of supplying fuel to the firepot, as when the door is opened such heating element is temporarily removed from the firepot, thus permitting the supply of fuel, and when the door is closed the heating element is again placed in position.

In accordance with the provisions of the patent statutes I have described the principles of operation of my invention, together with the device which I now consider to represent the best embodiment thereof; but I desire to have it understood that the device shown is only illustrative, and that the invention may be carried out by other means and applied to uses other than those above set out.

I claim—

1. A water heater comprising a firepot, a door to close the opening to said firepot, a projection extending from the back face of

the door inwardly within said firepot, said projection being in the form of a hood having a single water compartment within its walls on all sides within the firepot, and 5 circulatory pipes connected with said compartment.

2. A water heater comprising a firepot, a door to close the opening to said firepot, a projection in the form of a hood extending 10 from the back face of said door inwardly within said firepot and having parallel double walls to constitute a single water heating compartment between said walls, and circulatory pipes connected with said 15 compartment.

3. A water heater comprising a firepot, a door to close the opening to said firepot, a projection extending from the back face of 20 said door inwardly within the fire pot and having a water compartment therein, hinge ears each comprising a bulbous formation on

the outer face of the door and having an enlarged water chamber therein communicating with the water compartment in said projection, hinge ears secured to the furnace frame, and hollow nipples projecting through the hinge ears on the door frame and secured to and having the openings in the nipples communicating with said chambers in the hinge ears upon door. 25

4. A water heater comprising a firepot, a door to close the opening to said firepot, a hollow projection extending from the back face of the door inwardly within the firepot and having double walls comprising a water 30 compartment, a draught passage extending from the face of the door through the hollow portion of said projection and through said water compartment to the back end of the door, and circulatory pipes connected 35 with said compartment. 40

JOSEPH McLEAN.
